UNITED STATES PATENT OFFICE.

ARTHUR WILLIAM STEVENSON, OF MANCHESTER, ENGLAND.

METHOD OF PRODUCING CARDBOARD RECEPTACLES.

1,179,674.

Specification of Letters Patent.

Patented Apr. 18, 1916.

Application filed August 13, 1914. Serial No. 856,568.

To all whom it may concern:

Be it known that I, ARTHUR WILLIAM STEVENSON, a subject of His Majesty the King of Great Britain and Ireland, residing 5 at Manchester, England, have invented a new and useful Improved Method of Producing Cardboard Receptacles, of which the following is a specification.

This invention relates to an improved 10 method of producing receptacles of cardboard or the like.

The object is to produce receptacles of the class hereinafter referred to more cheaply and speedily than heretofore possible with a resultant article of manufacture of an improved form.

According to this invention it is proposed 20 to employ a blank free from projecting portions having slits at certain points therein. Adhesive is applied about said slits and the blank is then forced into a heated die so that the edges thereof are turned up to form the sides of the receptacle the slit portions overlapping to form double thicknesses or corners and being at the same time secured together by the adhesive and pressure and molded so that a finished article 25 is produced in a single operation.

According to one method of carrying out 30 the invention a blank of cardboard or the like having rounded corners is first obtained and this blank is then slit at say four points from the edge a certain distance inward, such slits being radial to a center or centers, and being located on lines which may subsequently form the centers of the rounded angle of the finished basket. The face of the cardboard which is to form the inside of the basket may then in one form 35 have glue applied to it at four points which are bounded on one side by an edge of each slit and the back is similarly glued at four points which are similarly bounded by an edge of each slit but which occupy points 40 on either side of the material which are not opposite to one another. Or the glue may be put on entirely inside or entirely outside. The glue may be allowed to dry before it is brought into use as hereinafter described. 45 The blank so prepared is placed in a heated die of suitable shape the operator preferably placing same so as to insure that the glued portions will fall into their correct position outside or inside the unglued parts

as the case may be. A plunger is then 55 brought down upon the blank causing the parts separated by the slits to pass one behind the other and so follow the lines of the sides of the die and plunger which may be of a tapered round cornered shape. As the 60 glued parts come finally together into position the heat softens same and the glued portions under the pressure adhere to the unglued portions. Thus the basket or the like is molded to shape and simultaneously fastened up or secured at a single operation 65 and in a single die. The corners of the basket thus overlap giving increased strength but owing to the pressure such parts are compressed so that the thickness 70 at these points is less than that of two ordinary thicknesses of the material.

The molding operation contemplated by the present invention is a true molding, as opposed to a mere turning up action which 75 has heretofore been employed in certain automatic receptacle making machines. In the method according to the present invention the depth of the box or article is not governed by the depth or length of the slits 80 owing to the true molding action of the plunger and heated mold. It is possible to employ blanks having V shaped slots therein instead of slits in carrying out the present invention. 85

The dies may be arranged to form a molded outstanding edge so that a shoulder is left inside the basket all or a part of the way around same which shoulder may receive and support a cover plate of cardboard or other material, which may be dropped onto same, or will form outside a rim or bead useful as an abutment for string when an external sheet of paper is to be employed as a cover. The molded rim 90 strengthens the receptacle and improves its appearance. In molding same a plain portion may be left say centrally at each side edge which will give a suitable surface for attaching a handle. This latter may be of 95 metal and of a known form secured by rivets to swivel and nest in the bottom of the basket or be turned outwardly for use.

The basket may be suitably perforated 100 for ventilation or other purposes and be formed of cardboard or the like waterproofed if desired and lined with another paper, which for some purposes and under

suitable conditions, may be a parchment or imitation parchment paper tin-foil or the like.

To enable the invention to be fully understood it will now be described by reference to embodiments thereof shown in the accompanying drawings in which:

Figure 1 is a plan view of the blank employed for forming a receptacle according to one form of the invention. Fig. 2 is a similar view showing the blank with its edges slightly bent up for insertion in the die or mold. Fig. 3 is a perspective view of one form of receptacle formed from the blank shown in Figs. 1 and 2, and Fig. 4 is a similar view showing the receptacle with an additional strengthening rim applied thereto.

Referring to Figs. 1 and 2, the cardboard or like blank 1 has its corners rounded and a radial slit 2 is formed at each corner. An adhesive such as glue is applied to the edges of the slit corners as indicated at 3 and the blank is then slightly bent at its sides causing the slit corners to overlap as shown in Fig. 2 and placed in a suitable die or mold. A suitable plunger then presses the blank in the mold preferably under the action of heat and the blank is molded and pressed into the form shown in Fig. 3, the slit corners overlapping and forming a double thickness at the corners of the receptacle as clearly shown. The heat softens the glue or other adhesive at the corners of the blank and the pressure causes the overlapped corners to bind firmly. The die is preferably designed to form a molded shoulder or rim 4 around the receptacle, said rim providing an internal ledge and an external shoulder which is useful if a paper or like cover is to be dropped therein or is to be placed over the receptacle to be secured by string.

The glue or other adhesive may be applied wholly on the inside of the portions *a* of the blank as shown or it may be applied on the outside or back of the portions *b*, or partly on each of the portions *a* and *b*. It is desirable that the adhesive should cover the whole of the overlapping surfaces.

The receptacle may be provided with a handle 5 pivotally attached to the inside of the receptacle and adapted to turn down and nest within same. At the points of attachment of the handle the die is preferably shaped to form inwardly projecting portions or pivot points 6 so that the handle may be turned easily into the nesting position. Or any suitable form of handle pivoted or otherwise may be provided. The receptacle shown in Fig. 4 is provided with a strength-

ening rim or edge 7 which may be applied by a suitable molding operation or by hand as desired.

It will be understood that by employing blanks of various shapes and positioning slits at various points therein receptacles of various shapes may be made according to the methods hereinbefore described. Round or circular receptacles for example may be formed, the slits being provided at suitable points in a suitably shaped blank.

Various materials other than cardboard may also be employed.

What I claim is:

1. The method of producing a receptacle of cardboard or the like consisting in slitting a cardboard or like blank which is free from projections at points about its corners, and applying an adhesive such as glue at such points, then under the action of heat molding and pressing said blank in such a manner that the edges are turned and the slit portions thereof caused to overlap and to be secured to form the sides and corners of the receptacle, the arrangement being such that the corners and the adjacent portions on each side thereof are composed of double thicknesses of material.

2. The method of producing a receptacle of cardboard or the like consisting in slitting a cardboard which is free from projections at points about its corners, and applying an adhesive such as glue at such points, then under the action of heat molding said blank in such a manner that the edges are turned and the slit portions thereof caused to overlap and to be secured to form the sides and corners of the receptacle a shoulder being also formed on the inside of the receptacle extending all the way around same.

3. The method of producing a receptacle of cardboard or the like consisting in slitting a cardboard which is free from projections at points about its corners, and applying an adhesive such as glue at such points, then under the action of heat molding said blank in such a manner that the edges are turned and the slit portions thereof caused to overlap and to be secured to form the sides and corners of the receptacle a shoulder being also formed on the outside of the receptacle extending part of the way around same.

In witness whereof I have hereunto set my hand in the presence of two subscribing witnesses.

ARTHUR WILLIAM STEVENSON.

Witnesses:

ERNEST CONN,
ALICE BOFFING.
